UNITED STATES PATENT OFFICE.

OTTO RANGNOW, OF PHILADELPHIA, PENNSYLVANIA.

TRUNK.

1,171,978.

Specification of Letters Patent. Patented Feb. 15, 1916.

Application filed September 10, 1915. Serial No. 49,911.

To all whom it may concern:

Be it known that I, OTTO RANGNOW, a citizen of the United States, residing at Philadelphia, in the county of Philadelphia and 5 State of Pennsylvania, have invented certain new and useful Improvements in Trunks, of which the following is a specification.

My invention relates to improvements in wardrobe trunks, and particularly relates to 10 a receptacle for carrying soiled linen in the wardrobe trunk.

The object of my invention is to construct a receptacle which is adapted to be held in a vertical position in a wardrobe trunk; a 15 further object of my invention is to construct the receptacle so that it will occupy a space in the trunk which is not available for any other purpose.

In the accompanying drawing in which 20 like references refer to like parts; Figure 1 is a perspective view of a portion of a wardrobe trunk illustrating my invention; Fig. 2 is a front view of the follower or garment compressor, showing the fastening devices 25 attached thereto for holding the receptacle upon the compressor; Fig. 3 is a vertical section on line 3—3 Fig. 2; Fig. 4 is a front elevation of the receptacle, detached; and Fig. 5 is a vertical section on line 5—5 Fig. 4.

Referring to the drawing, 1 represents a portion of a wardrobe trunk, in which the garments are placed by hanging them on coat hangers, which are suspended from the tracks 2 and 3 secured in the trunk. A compressor consisting of a frame 5, as shown in 35 Fig. 2, is provided to compress the garments against the back wall of the trunk. As the garments are more bulky at the top of the trunk, the compressor frame 5 stands at an 40 oblique angle, as shown in Fig. 1, and my soiled linen receptacle is adapted to occupy the space thus formed at the lower portion of the trunk.

The soiled linen receptacle 6 consists of a 45 back portion 7, made of rigid material and a front portion 8, made of flexible material, secured to the edges of the back portion 7, thus forming a bag adapted to be compressed when empty and to expand to accommodate 50 articles which may be placed in the bag.

The receptacle has an opening formed at the top thereof and the edges of the flexible material forming the opening are held in the closed position by fastening devices 10, preferably glove clasps, one of the members of

each fastener being secured to the rigid back 7 and the other member being secured to the said flexible material forming the front portion 8.

The receptacle is secured to the compressor 60 frame 5, in the following manner; at the lower portion of the compressor frame is provided a cleat or angle plate 12 into which the lower edge of the back portion 7 of the receptacle is inserted. The upper portion of 65 the receptacle is held by fastening devices 13 and 14 which consist of straps 15 secured to the compressor frame 5, each strap carrying one member of a clasp 16. The other member of the clasp 16 is secured upon the rigid 70 back portion 7 of the receptacle 6. The flexible front portion 8 of the receptacle, when closed, partially conceals the fastening device 16 at the top of the receptacle.

It will be seen that the receptacle may be 75 removed from the trunk by simply detaching the upper fastening devices 16 and lifting the receptacle off the angle plate 12.

The shoe box 20, usually found in wardrobe trunks, can be used with my soiled linen 80 receptacle, as the latter hangs above the shoe box, as shown in Fig. 1.

Having thus described my invention I claim and desire to secure by Letters Patent:

1. In a trunk the combination of a garment compressor adjustably mounted within the trunk, a soiled linen receptacle having a front portion of flexible fabric forming an expansive bag and means for securing the 85 said receptacle to the said compressor. 90

2. In a trunk the combination of a garment compressor adjustably mounted within the trunk, a soiled linen receptacle having a front portion of flexible fabric forming an expansive bag, said receptacle having a rigid 95 back portion, and means for securing the upper and lower edges of the back portion to the said compressor.

3. In a trunk the combination of a compressor frame, a receptacle having a rigid 100 back portion and a flexible front portion, an angle plate upon the lower portion of the compressor frame to support the receptacle, and fastening devices for holding the upper portion of the receptacle against the compressor frame. 105

4. In a trunk the combination of a receptacle having a flexible front portion, said receptacle having an opening formed adjacent to the top thereof, a compressor adjust- 110

ably secured in the trunk, and means for securing the receptacle in an upright position upon the compressor.

5. In a trunk the combination of a receptacle having a back portion of rigid material and a front portion of flexible material with the edges thereof secured to the said back portion, the said flexible front portion being divided at the upper edge thereof 10 to form an opening, fastening devices at-

tached to the back and front portions for holding the latter in the closed position, and means for securing the receptacle in a trunk.

In testimony whereof I have affixed my signature in presence of two witnesses.

OTTO RANGNOW.
